UNITED STATES PATENT OFFICE.

KIRK K. WRIGHT, OF BUFFALO, NEW YORK, ASSIGNOR TO R. G. WRIGHT & CO., OF BUFFALO, NEW YORK.

HEAT EXCHANGER.

Application filed November 17, 1922. Serial No. 601,601.

To all whom it may concern:

Be it known that I, KIRK K. WRIGHT, a citizen of the United States, residing at Buffalo, in the county of Erie and State 5 of New York, have invented a new and useful Improvement in Heat Exchangers, of which the following is a specification.

This invention relates to heat exchangers for liquids of the kind in which the liquid 10 to be cooled or heated passes over a series of horizontally arranged, superimposed tubes through which a temperature changing medium is circulated.

The invention is primarily intended to 15 be used as a cooler for liquids and particularly for milk or other liquids which necessitate a thorough cleansing of the portions 20 of the apparatus with which the liquid comes into contact, but it is not intended to limit the invention to use in connection 25 with coolers for such liquids, since the apparatus may be used advantageously in connection with either the heating or the cooling of any liquid.

In coolers of this kind, it is necessary in order to have the cooler operate at its full efficiency, to provide means for ensuring that substantially equal quantities of liquid flow down on opposite sides of the cooler and 30 for this purpose in coolers as heretofore constructed, it has been found necessary to place inserts between the adjacent superimposed horizontal tubes or pipes in such a way as to prevent the liquid from flowing 35 from one side of the vertical series of pipes to the other side thereof, and various means have been devised for this purpose, all of which, however, add greatly to the expense 40 of the cooler or are otherwise objectionable.

The objects of this invention are to provide a cooler consisting of a series of substantially horizontal, superimposed pipes which are arranged in such close proximity to each other as to permit the adjacent tubes 45 to be connected by means of solder; also to provide improved means for connecting the tubes to the headers arranged at the sides thereof so as to permit the tubes to be placed substantially into contact with each other 50 without weakening the construction of the headers; and also to improve the construction of cooling devices of this kind in other respects hereinafter specified.

In the accompanying drawings:

Fig. 1 is a side elevation, partly in sec-

tion of a milk cooler embodying the invention.

Fig. 2 is a fragmentary longitudinal central sectional elevation thereof.

Fig. 3 is a fragmentary perspective view 60 thereof.

Fig. 4 is a fragmentary elevation of one of the headers of the cooler, showing the same with the tubes omitted therefrom.

Fig. 5 is a transverse sectional elevation 65 on line 5—5, Fig. 2.

Fig. 6 is a perspective view of a tube of the cooler.

Fig. 7 is a perspective view showing two cooler tubes secured together and detached 70 from the header.

Milk coolers of this kind are generally provided with a pair of headers A and A' arranged at opposite ends of the cooler, and pipes B carrying the cooling medium terminating in the headers, the headers being preferably provided with a plurality of partition walls a, which cause the cooling medium to flow from one pipe to an adjacent pipe. a' and a² represent respectively the 75 inlet and discharge pipes for the cooling medium. C represents the usual supply or distributing trough arranged above the cooler and provided in its bottom with two series of discharge holes or orifices b and b' through which the milk or liquid to be cooled or heated may be discharged to opposite sides of the upper pipe of the cooler. These discharge orifices are so arranged 80 with reference to the upper pipe that approximately the same amount of liquid passes to each side of the cooler, so that both sides of the apparatus will be utilized 85 for cooling the liquid.

In order to arrange the pipes B so that each pipe either touches the adjacent pipe or pipes or is arranged in close proximity thereto, it would be necessary to bore holes in the headers for the ends of the pipes which would be either tangent or else in 100 such close proximity to each other as to leave only a very thin portion of metal between adjacent holes. It is, however, impossible to accurately drill holes in such a manner that they will be tangent, since the 105 cutting tool will tend to move during its cutting operation toward the adjacent hole in the header. For the same reason it is necessary to leave sufficient thickness of metal between holes so that the metal 110

between adjacent holes will be of sufficient strength to prevent deformation by a cutting tool when operating in close proximity to the edge of a hole. For these reasons it 5 has heretofore been found impractical to machine the headers so as to bring the adjacent tubes into contact or into close proximity to each other.

In order to overcome this difficulty, I 10 have provided a construction whereby the holes in the headers may be drilled at sufficient distances apart so that the metal between adjacent holes will be of sufficient thickness and strength to make accurate 15 machining of the headers practical. This is done by securing short sleeves or inner tubes D into the ends of each cooling tube B, each of these insert tubes D extending beyond the end of the tube B and being 20 adapted to extend into a hole d in the header. Any suitable means may be employed for securing the insert tubes or sleeves in place in the outer or cooling tubes, the insert tubes 25 being generally soldered into the outer tubes. Consequently, the holes in the header may be drilled far enough apart so that the metal between holes is twice the thickness of the metal in the tubes B, which is sufficient to 30 make accurate machining easily possible. Consequently, when the cooling tubes B with the insert tubes D therein are assembled into 35 the headers, the insert tubes D will be spaced apart, but the outer tubes B will be tangent, or in close proximity to each other. The insert tubes extend slightly beyond the ends of the outer tubes, and the holes d in the headers are preferably bored of sufficient depth so that the ends of the holes will form 40 stop shoulders d' against which the ends of the insert tubes engage to facilitate the correct assembling of the cooler.

After the tubes and headers have been assembled, the tubes are preferably connected or secured together by means of bonding 45 material, such as solder or other molten metal, in such a manner that the bonding material will fill the spaces or angular recesses between adjacent tubes. These angular recesses cause the molten metal or other 50 material to be readily retained therein, so that the adjacent portions of the tubes are connected by strips E of solder or other metal, see Fig. 3, of wedge shaped cross section. This closes the angular or wedge 55 shaped recesses and thus positively prevents the liquid which is being heated or cooled from passing from one side of the cooler to the other and also greatly facilitates the cleaning of the heat exchanger in that the 60 solder or other material E fills those por-

tions of the spaces between adjacent tubes which are most difficult to clean and which most readily collect dirt or other foreign matter. The solder or other material E at the same time forms a connection between 65 the several tubes which greatly strengthens the apparatus.

A heat exchanger constructed as described, has the advantages over apparatus of this kind heretofore built in that the construction described can be produced at a lower cost and at the same time possesses greater strength than similar apparatus heretofore constructed.

I claim as my invention:

1. In a heat exchanger, the combination of a plurality of tubes of substantially uniform diameter, headers with which said tubes communicate and provided with a series of holes of smaller diameter than the outside diameter of said tubes each hole being spaced apart from adjacent holes, insert sleeves projecting into the ends of said tubes and into said holes in the headers, said sleeves being of substantially uniform diameter throughout their lengths whereby said tubes may be placed in close proximity or in contact, and bonding material forming a connection between said tubes and filling the spaces between adjacent tubes. 75

2. In a heat exchanger, the combination of a plurality of tubes, headers with which said tubes communicate and provided with a series of holes of smaller diameter than the outside diameter of said tubes, insert members arranged within said tubes and extending into said holes and serving to space said tubes in close proximity to each other and forming a rigid connection between said 95 headers and said tubes, and a bonding connection between adjacent tubes which fills the spaces between tubes and forms a connection between tubes. 100

3. In a heat exchanger, the combination of a plurality of tubes, headers with which 105 said tubes communicate and having holes of smaller diameter than the outside diameter of said tubes, insert members fitting closely into said tubes and into said holes and serving to space said tubes in close proximity 110 to each other, and to form a rigid connection between said headers and said tubes, stop portions in said holes with which said insert members are adapted to engage to limit the extent to which said insert members may 115 enter said holes, and a metallic bonding connection between adjacent tubes which fills the sharp angled recesses between adjacent tubes.

KIRK K. WRIGHT.
